SEWING MACHINE ATTACHMENT

Fritz Gegauf, Steckhorn, Switzerland, assignor to
 Fritz Gegauf's Söhne Aktiengesellschaft, Steck-
 born, Switzerland.

Application December 7, 1943, Serial No. 513,255
 In Switzerland August 17, 1942

2 Claims. (Cl. 112—260)

1.

This invention relates to sewing machine attachments serving for enlarging the fabric supporting area of sewing machines in which the loop-taker is arranged in a freely projecting machine arm.

For carrying out certain kinds of sewing operations in sewing machines of this type it is necessary, for producing perfect work, to enlarge the relatively small fabric supporting area presented by said freely projecting arm.

According to the present invention for this purpose, an attachment constituting a table for enlarging the fabric supporting area is arranged, advantageously, superimposed on said arm so as to be sustained by the latter after being set in position thereon.

By these means the fabric supporting area can be enlarged in a relatively simple manner within the embrace of the freely projecting arm so that at the same time a fabric supporting surface of a correspondingly great stability is obtained.

Said table being thus adapted to be placed on the freely projecting arm of the sewing machine may be provided with a stay, advantageously, a pivotal stay which is intended to rest on the means supporting the sewing machine. By these means the table is adapted to carry a relatively great load without risk of being detrimentally affected even if the fabric supporting area provided by it is offset relative to the freely projecting arm of the sewing machine to a considerable extent.

Furthermore, clamping means may be arranged by means of which the table that can be set on the freely projecting arm of the sewing machine is fixable in position on said arm. By this means it is intended to ensure, with the aid of simple, reliably functioning means, longitudinal alignment between the arm of the sewing machine and the table for enlarging the fabric supporting area, whereas the correct position of the table on said arm in regard to the circumference of the latter is positively ensured by correspondingly shaping the cross section of the machine arm and fitting the table to the latter.

Three embodiments of the invention are illustrated, by way of example only, in the accompanying drawings in which

Fig. 1 shows a first embodiment in a longitudinal elevation with the table set on the freely projecting arm of the sewing machine;

Fig. 2 is a cross section of the table;

Fig. 3 shows a longitudinal section of said embodiment;

2

Fig. 4 is a top plan view of Fig. 1 on a smaller scale;

Fig. 5 shows a longitudinal elevation of a second embodiment of the invention with the table set on the freely projecting arm of the sewing machine;

Fig. 6 is a sectional plan view of Fig. 5;

Fig. 7 is a cross section of the second embodiment;

Fig. 8 and 9 show a stay in two different sectional views;

Fig. 10 shows a third embodiment of the invention in a longitudinal elevation with the table set on the freely projecting arm of the sewing machine also in this case;

Fig. 11 is a cross section on the line XI—XI in Fig. 10, and

Fig. 12 is a sectional part view on the line XII—XII in Fig. 11.

In the first embodiment of the invention shown in Figs. 1 to 4 the numeral 1 designates the freely projecting arm emerging from the base 2 of the machine and carrying at its outer end face a pivotal closure cap 3. By pivotally lowering the closure cap 3 free access to the loop-taker 4, which is accommodated in the projecting arm 1 at the side of the feed dog 5, is provided in a known manner. The loop-taker 4 has a spool casing 7 secured therein against detachment by means not shown, and may, for example, be enclosed by the closure cap 3. The loop-taker is driven by a shaft 6. The closure cap 3 is given a cross sectional form corresponding to that of the projecting arm 1 and its outer surface is bulged outwardly relative to the outer end face of the arm 1.

Onto the freely projecting arm 1 is pushed from the outer end face thereof a table 8 which is provided with a flat top plate 9 and on the under side of which is arranged a yoke 10 for the reception of the arm 1. The yoke 10 is composed of two stirrups 11 which are arranged one behind the other in regard to the longitudinal axis of the projecting arm 1 (Fig. 2) at a certain distance apart, the stirrups being adapted to the cross sectional form of the arm 1 and interconnected at their lower apex by a bridge piece 12. The piece 12 is provided on the side thereof facing towards the projecting arm 1 with a recess for engagement with a spring-loaded locking ball 13 which is arranged in a sleeve 14 on the arm 1 and serves, when cooperating with the said recess in the bridge piece 12 on the yoke 10, for securing the table 8 in position on the arm 1 in the axial direction of the latter.

The table 8 is immovably fastened in the cir-

cumferential direction on the projecting arm 1 by a locking bolt 15 (Fig. 3) seating in a hole 16 in the wall surrounding the hollow interior of the arm 1. The table top 9 is provided with an oblong aperture 17 for interengagement with the projecting arm 1 so that the plane upper surface of the latter is flush with the upper surface of the table top 9.

Therefore, on the sewing machine a plane supporting surface of an appropriate area for the material to be sewn in the machine is provided. To the longitudinal marginal portions bordering the aperture 17 of the table top 9 a resilient lagging 18 consisting, for example, of textile material, is applied and a resilient lagging 19 is also applied to both stirrups 11 of the yoke 10 for the purpose of protecting the surface of the projecting arm 1, when the table 8 is slid on or off the arm 1, and at the same time obtaining snug bearing engagement between the table and the projecting arm 1. Due to the table 8 being secured directly to the arm 1 these two parts practically form together a rigid unit. The dismounting of the table 8 is effected by axially retracting the latter from engagement with the projecting arm 1 against the resistance opposed thereto by the locking ball 13.

In opposite relation to the throat plate 20 a pivotal lid 22 is arranged in an opening 21 in the table top 9 joining with the aperture 17 and being wider than the latter. If the pivotal lid 22 is swung from the position shown in full lines in Fig. 3, in which the lid is flush with the upper surface of the table top 9, into the chain-dotted position of inclination shown in this figure the closure cap 3 of the projecting arm 1 is accessible from above through the opening 21 then being uncovered, whereby access from above is provided for also for the spool casing and the loop-taker while the table 8 remains in position on the projecting arm 1. The sliding of the table 8 on as well as off the projecting arm 1 can thus be readily carried out without any further provisions so that it is possible to readily enlarge and reduce again the area of the fabric supporting surface of the sewing machine as desired. If required the table may be adapted to be placed on the projecting arm of the sewing machine also in some other fashion than by slidably engaging it therewith.

Dependent upon requirements, the table may be sustained by any other suitable supporting means than the projecting arm, for example, by an attachment carrier plate arranged on the body portion of the machine, or the like.

In the second embodiment of the invention as shown in Figs. 5 to 9 the yoke 10 is constituted by a stirrup 10' provided with a reinforcing rib. The edge of the squared off table top 9 removed from the projecting arm 1 of the sewing machine is provided with a pivotal stay 25 which is pivotally mounted by means of two eye-bearings 26 on two bolts 27 that are arranged on the table top 9 in coaxial relation to each other. The pivotal stay 25 is, if taken as a whole, substantially in the form of a stirrup the arms of which serve as supporting legs 28 into the free ends of each of which a friction producing plug like castor 29, for example of rubber, is sunk. In its position of use as shown in Fig. 5 the pivotal stay 25 rests on a plane support 30 for the, what may be termed, table supported sewing machine and it will be seen that the stays form an obtuse angle with the table top 9. With the pivotal stays 25 in this position these bear against the respective edge 75

of the table top 9 by means of the edge 31 (Fig. 9) of their connecting bar by which means the angular range of the stays and thus the angular position of the stays is defined relative to the table top 9 and thus to the support 30 of the sewing machine.

The table top 9 thus supported at its end removed from the projecting arm 1 of the sewing machine withstands any loading that may arise in actual practice without risk of being detrimentally affected irrespective of the extent to which the fabric supporting area formed by the table top 9 may be offset from the said projecting arm 1. The sewing woman can therefore, for example, rest with her arm on the table 8 without restraint. Obviously the structural form of the pivotal stay may vary within wide limits. Thus, the stay may be composed of several parts that can be pivotally adjusted independently of each other instead of constituting an individual unit. Further the stay need not necessarily be in form of a pivotal stay.

The operation of slidably engaging and disengaging the table 8 with or from the projecting arm 1 respectively can be readily effected without any further provisions so that it is possible to enlarge the fabric supporting area of the sewing machine as well as reduce said area again in a quick manner. In the position of non-use of the table 8 the pivotal stay 25 can be swung towards the under side of the table top 9, that is, pivotally moved into contacting engagement with said side in the direction of the arrow shown in Fig. 5.

In the third embodiment of the invention shown in Figs. 10 to 12 a clamping device cooperates with the projecting arm 1 of the sewing machine below said arm. This device comprises a control lever 35 connected with a spindle 32 which is carried by a bearing 33 arranged in the yoke 10. On the spindle 32 a circular disc 34 is arranged in eccentric relation thereto and is adapted to engage in a recess in the yoke 10. By appropriately pivotally displacing the lever 35 the eccentric disc 34 can either be pressed against a counter surface presented to it by the projecting arm of the sewing machine or be moved out of engagement with said surface. If the clamping lever 35 is in the position I the eccentric disc 34 is ineffective, whereas with the clamping lever 35 being in position II said disc is pressed against the machine arm 1 and consequently the table 8 is urged against the machine arm 1 from above by means of the longitudinal marginal portions of the aperture 17 in the table top 9 so that the table 8 is fixed to the machine arm 1 and withstands tension exerted thereon in the axial direction. On swinging the clamping lever 35 from the position II back into position I the table 8 can be pulled off the machine arm 1 or be pushed thereon as required.

I claim:

1. In sewing machine attachments for enlarging the fabric-supporting area of sewing machines having the loop-taker means included in an arm freely projecting from said machine, a table having a fabric-supporting top surface, said table having an opening formed therein, a hollow projecting machine arm having a fabric-supporting top surface for mating said top surface of said table, a casing having a spool carrying the sewing thread accommodated in the hollow of said arm, a pivotal lid associated with said opening in said table for covering the latter and when uncovering it on being swung upwardly providing access to said casing from above, and

mounting means interposed between said table and said projecting arm for sustaining said table on said arm on being placed on the latter in a position wherein said two fabric-supporting surfaces are mating each other for enlarging the fabric-supporting area of said sewing machine.

2. In sewing machine attachments for enlarging the fabric supporting area of sewing machines having loop-taker means included in an arm freely projecting from said machine, a machine support, a table carrying a table top having a fabric-supporting top surface, a freely projecting machine arm having a fabric-supporting top surface for mating said top surface of said table, means for arranging said table on said projecting arm in a position wherein said two fabric supporting surfaces are mating each other for enlarging the fabric-supporting area of said sewing machine, and a pivotal stay swingably arranged at the end of said table remote from said 20

projecting arm for resting on said machine support when said table is in said position, said stay being swingable into contact with the under side of said table top when said table is not being used.

FRITZ GEGAUF.
